UNITED STATES PATENT OFFICE.

ISAAC S. PURCELL, OF OAK PARK, ILLINOIS, ASSIGNOR TO TENTOBED COMPANY, OF CHICAGO, ILLINOIS, A CORPORATION OF ILLINOIS.

SEPARABLE COT.

1,323,201.

Specification of Letters Patent. Patented Nov. 25, 1919.

Application filed December 8, 1916. Serial No. 135,789.

To all whom it may concern:

Be it known that I, ISAAC S. PURCELL, a citizen of the United States, residing at Oak Park, in the county of Cook and State of Illinois, have invented certain new and useful Improvements in Separable Cots; and I do hereby declare the following to be a full, clear, and exact description of the invention, such as will enable others skilled in the art to which it appertains to make and use the same.

My invention relates to cots, one of its general objects being to provide a foldable or collapsible cot which may be stored in a quite small space and which may quickly be expanded into an unusually strong and firm bed. Other objects are to provide an article of this class having a spring tensioned bed-bottom and one which will easily and automatically tension this bed-bottom when the cot is being erected; to provide a foldable cot which may readily be separated into four or more parts, each of which parts can easily be carried by a single boy scout or the like; to provide simple and effective means for bracing various parts of the frame of the cot and for preventing an accidental detaching of the frame; and to provide simple means for maintaining the foldable side rail portions of the frame rigid when the cot is erected, and to provide effective and cheaply constructed feet for preventing the legs from penetrating soft soil unduly.

Still further objects will appear from the following specification and from the accompanying drawings, in which—

Figure 1 is a plan view of the erected cot. Fig. 2 is a side elevation of the same. Fig. 3 is an enlarged plan view of the hinge portion of one of the side rails of the cot.

Figs. 4 and 5 are two fragmentary elevations, taken at right angles to each other and showing the method of locking one end of the transverse brace to one of the intermediate legs.

Fig. 6 is a fragmentary side view of one of the intermediate legs and the parts adjacent thereto.

Figs. 7 and 8 are enlarged transverse sections through a side rail, taken respectively along the line 7—7 and 8—8 of Fig. 3.

Fig. 9 is a perspective view of the lower end of one of the intermediate legs. 55

Fig. 10 is a similar view showing the foot of one of the end legs.

Figs. 11 and 12 are perspective views showing two types of tip constructions for the end rails. 60

Fig. 13 is a fragmentary perspective view showing how the braces fold against the cross-bar.

Fig. 14 is an enlarged perspective view of the tip of one of the end legs of the cot. 65

While my invention may be applied with substantially equal facility and advantages to cots having various types of flexible bed-bottoms and having frame portions of widely differing materials, it is particularly adapted for use with frames composed largely of channel steel and with bed-bottoms including spring tensioned fabrics. Hence it is shown in such an embodiment in the accompanying drawings, though I wish 70

it understood that the construction and arrangement might be varied in many ways without departing from the spirit of my invention. In the drawings, the cot frame consists primarily of a pair of side rails, 80

each foldably hinged at one side of its middle and each having three legs pivoted to it, together with a pair of end rails 1 equipped for slidably engaging the tips of the respective side rails and having a metal 85

bed-bottom spring 2 stretched between these end rails; also, a detachable stiffener 3 spacing the intermediate legs 4 and connected to the nearer end legs 5 by braces 6. Each side rail is desirably made of two angle 90

steel parts facing in opposite directions, such as a long portion 7 having a flat side uppermost, and a shorter portion 8 having a horizontal web of the angle at its lower edge. The rail portions 7 and 8 are preferably pivoted upon a pin 9 located at some distance from the end of the longer bar 7 but close to the end of the shorter section 8, and the former preferably carries at its extreme end a vertical flange 10 coöperating 95

with the adjacent vertical web of the rail section 7 to afford a socket for slidably receiving a part of the vertical web of the rail section 8, as indicated in Fig. 3. This socket serves to prevent a relative lateral motion of 100 the rail sections; and when the two sections

are thus interlocked, they are prevented from moving about their pivotal connection 9 by a latch 11 pivoted to the section 7, and adapted to be swung over the adjacent part 5 of the section 8 as shown in Figs. 3 and 6.

Instead of permanently securing either one of the end rails to the side rails, I preferably equip both end rails with tips arranged for slidably interlocking with the 10 ends of the side rails. For example, the end rail may consist of an angle steel bar having a wood stiffener bolted within its angle as shown in Fig. 12, and one web of the angle steel may be cut short so that the other web 15 can be formed into a socket as shown in the same figure. This socket can readily be slipped over one end of one of the side rails, the extent of the sliding being limited by a suitable stop carried by the side rail, such 20 as a pin 12. Both the socket and the stop construction may be varied considerably, as shown for example in Fig. 11, where the extended web of the angle steel is turned over until its tip buts against, a portion of 25 the other web and where the stop 12^a is formed by a lug punched from the web of the side rail. In either case, it will be obvious that the stop limits the extent to which the tip of the side rail enters the socket 30 formation on the end rail. Hence, the bed-bottom may easily be placed in position by sliding one of the end rails into engagement with the tips of the side rails (as shown at 35 the right hand end of Fig. 2) and then slipping the other end rail into operative 40 position while the side rail sections 8 are tilted as shown in dotted lines, after which the depressing of the sections 8 to their normal horizontal positions tensions the bed-bottom and draws the left-hand end rail firmly into position.

To prevent an accidental folding or tipping of the legs, I preferably latch each leg by means of a brace 14 pivoted to one of the 45 side rails and engaging a suitably coöperating formation on the leg, as for example, by means of the hook and pin formations shown in the drawings. I also preferably prevent an accidental detaching of each hook 50 by using a spring latch, which latch is desirably also used for latching the hook ends of the spreader 3. This spring latch is desirably composed of a single piece of wire 15 having portions extending through two 55 perforations in the leg on which it is mounted and having the latching portion of the wire adapted to be pressed close to the leg by pressing the same toward the leg and causing the free tip to project through one of 60 these perforations, as shown in Figs. 4 and 5. To prevent the tips of the legs from unduly entering any soil, I preferably provide each leg with a foot formation affording a 65 much greater area than the cross-section of the angle steel of which the leg is made. In

the case of the intermediate legs 16, which legs fold into the interior of the angle of the rail section 7, the foot formation is desirably made by cutting one web of the angle steel shorter than the other and bending the 70 projecting portion 17 of the other web transversely so as to afford a flat surface flush with the tip of the shorter web, as shown in Fig. 9. On each end leg 18, the foot formation is desirably afforded by splitting the 75 tip of the leg along the angle and then turning the loosened portion of each web transversely and outwardly as shown in Fig. 10, thereby permitting each leg 18 to be folded over the exterior of the angle of the rail 80 section 7 and parallel to the latter.

The braces 6 are preferably pivoted to the stiffener 3 at pivot points spaced both from each other and from the ends of this stiffener, so that when in use they will 85 diverge angularly as shown in Fig. 1; and these braces are preferably arranged so as to lie respectively above and below the horizontal web of the stiffener 3, thereby permitting these cot portions to be folded into 90 a compact form as partially indicated in Fig. 13. Each of these braces is desirably made of a flat bar of steel having one end twisted at right angles to the general plane 95 of the bar and equipped with a hook formation adapted to engage a suitably located pin or lug on one of the end legs 18, the movement of the hook end being permitted by the resiliency of the brace.

It will be evident from the above description and from the drawings that the cot of my invention can be easily and quickly erected or knocked down without the use of any tools, and that when erected it will be unusually firm. Moreover, when dismounted, 105 it readily separates into four portions, each of which may easily be carried by man or boy, and which portions may be stored either separately or jointly in a comparatively small space, viz.: two side members, 110 each consisting of a pair of pivotally joined rail sections and of three legs and two braces pivoted to these sections; one bed-bottom section consisting of the bed-bottom fabric (here shown as of wire) and of the 115 end rails; and one spreader with two braces pivoted to the same. To facilitate a compact joint storing or shipping, the longer side rail sections are preferably of no greater length than the end rails, but I do not wish 120 to be limited to these proportions or other particulars of the embodiment herein disclosed, nor to its comprising all of the described features.

I claim as my invention:

1. In a cot having end legs and a pair of intermediary legs, a spreader spacing the latter, and braces having one end connected to the spreader and their other end connected directly to the end legs respectively. 130

2. In a cot having end legs and a pair of intermediary legs, a spreader spacing the latter, and braces pivoted to the spreader and connected directly to the end legs respectively.
  3. In a cot having end legs and a pair of intermediary legs, a spreader detachably interlocked with the latter, and two braces pivoted to the spreader at a distance from each other and from the intermediary legs, said braces being detachably interlocked respectively with two of the end legs.
  4. In a cot, the combination of a side rail, an end rail of angle steel having one web
- extended beyond the end of the other web, 15
the extended web portion being formed into a socket for receiving an end of the side rail.
5. In a cot, the combination of a side rail, an end rail of angle steel having one web 20
extended beyond the end of the other web,
the extending web portion being formed into a socket for receiving an end of the side rail, and a stop on the side rail for limiting the entrance of the latter into said socket. 25

Signed at Chicago, Illinois, December 5th, 1916.

ISAAC S. PURCELL.
